PIPE WRENCH

James W. McNeil, Hoboken, N. J., assignor of
one-half to Peter Thorsen, Hoboken, N. J.

Application October 18, 1938, Serial No. 235,549

3 Claims. (Cl. 81—69)

This invention relates to improvements in pipe wrenches or tongs, and the invention has reference, more particularly, to a novel pipe wrench or tongs of the kind provided with an adjustable flexible gripping means, such as a chain, to embrace and grip the work.

This invention has for an object to provide, a novel pipe wrench or tongs comprising a bifurcate head having a lever member pivotally connected therewith, and a flexible gripping means, preferably in the form of a chain, affixed by one end to one branch of said head, the other branch of said head having pivotally mounted coupling means to which the free end portion of the chain 10 may be detachably engaged so that the chain embraces the work, and a link means interconnected between the inner extension of said lever member, whereby movement of the latter in one direction swings said pivoted coupling means to 15 constrict the chain into gripping relation to the work, while movement of said lever member in the opposite or retractive direction swings back said coupling means to slacken the chain to release its grip upon the work, thereby permitting 20 the chain and head to slip relative to the work to recover position for a succeeding operative stroke of the wrench or tongs.

The invention has for another object to provide in a pipe wrench or tongs as above characterized, a novel coupling means releasably engageable by the free end of the work gripping chain, so constructed and arranged as to facilitate initial operative engagement and adjustment of the chain in work embracing position, and 25 which provides means selectively engageable by the chain so that the latter may be disposed around the work in a desired degree of initial slackness relative thereto.

The invention has for another object to provide 30 in a pipe wrench or tongs characterized as above set forth, means for yieldably interlocking the head and lever member when the gripping chain is relaxed, whereby retractive movement may readily and quickly be transmitted by the lever member to the head and relaxed chain.

Other objects of the invention, not at this time more particularly enumerated, will be understood from the following detailed description of the same.

An illustrative embodiment of the novel pipe wrench or tongs is shown in the accompanying drawing, in which:

Fig. 1 is a side elevation of the pipe wrench or tongs according to this invention, with the work embracing chain in coupled disposition relative

to the work and as initially relaxed; Fig. 2 is a transverse vertical sectional view, taken on line 2—2 in Fig. 1; Fig. 3 is another transverse vertical sectional view, taken on line 3—3 in Fig. 1, but drawn on an enlarged scale; and Fig. 4 is a sectional view with one side of the head removed, and showing the coupled work embracing chain tightened to gripping relation to the work ready for an operative stroke of the wrench or tongs.

Similar characters of reference are employed in the hereinabove described views, to indicate corresponding parts.

Referring to the drawing, the novel pipe wrench or tongs has a bifurcate head comprising a pair of laterally spaced head plates 10, each having divergent branches 11 and 12 at the forward end to provide a V-shaped work engaging face. The converging marginal portions of said head plates which form the V-shaped work engaging face of the head thus provided, are preferably equipped with serrated gripper jaw means 13, which are suitably affixed to said head plates.

Entering from the rear of the head, to lie between the head plates 10 thereof, is a wrench actuating lever member 14 which is fulcrumed on a transverse bearing or fulcrum pin 15, the latter being affixed to and between said head plates 10. Said lever member 14 has an inner lever extension 16 projecting forwardly from the fulcrum joint within the confines of said head plates 10. Extending rearwardly and outwardly from the lever member body is a handle extension 17 of suitable length.

Non-detachably anchored upon a cross-pin 18, which is affixed to and between the branches 11 of the head plates 10 is a flexible gripping means, preferably in the form of a link chain 19, the ends of the transverse coupling pins of which project laterally and exteriorly from the chain sides to provide coupler studs 20.

Affixed to and between the branches 12 of the head plates 10 is a transverse pivot pin 21. Pivotally mounted on said pivot pin 21 is a coupler means comprising a pair of laterally spaced parallel coupler members 22 of bell-crank form, the same having dependent from one side of the fulcrum point coupler arms 23, provided along their rearward marginal portions with one or more chain engaging hooks 24, and lever arms 25 rearwardly extending from the other side of the fulcrum point. Said lever extension 16 of the actuating lever member 14 is provided with a bifurcate free end to receive one end of a link 26, which is pivotally connected with said lever extension 16 by a transverse pivot pin 27. The op-

posite end of said link 22 is disposed between the free ends of the coupler member lever arms 25, being pivotally connected therewith by a transverse pivot pin 28.

5 Means are provided for yieldably interlocking the head and actuating lever member 14 in a position to dispose the chain coupling means so as to hold the chain 19, as coupled therewith, in an initial relaxed condition relative to work embraced by said chain. An illustrative form of such means comprises a detent structure of the ball check type. This detent structure includes a transverse chamber or bore 29 extending through said lever member 14, and provided with 10 a fixed internal annular seating shoulder 30 to seat a detent ball 31 for projection from one side of the lever member 14 in normal engagement with and in a receiving socket 32 provided in the opposed contiguous face of the adjacent 15 head plate 10. At the other end of the chamber or bore 29 is detachably affixed a thimble 33 provided with an internal annular seating shoulder 34 to seat a second detent ball 35 for projection from the opposite side of the lever member 14 in 20 normal engagement with and in a receiving socket 36 provided in the opposed contiguous face of the adjacent opposite head plate 10. Arranged within the chamber or bore 29 between the detent balls 31 and 35 is a compression spring 37 to 25 exert a yielding outward thrust upon said detent balls. If desired, the ends of the spring 37 may be provided with ferrules 38 by which said detent balls are engaged.

In the use of the novel pipe wrench or tongs, 30 the jaws of the head are applied against the pipe P, or other element to be moved, the lever member 14 being disposed in normal initial position relative to the head, i. e. in the position shown in Fig. 1 in which it is yieldably held by 35 the engagement of the detent balls 31 and 35 with the sockets 32 and 36 of the respective head plates 10. When the lever member 14 occupies such normal initial relation to the head 10, the lever extension 16 is upswung to a position to 40 turn the pivoted coupler members 22 to a normal initial position wherein the coupler arms 23 are swung inwardly toward the pipe P, and thus in a position to receive attachment thereto 45 of the free end portion of the chain 19 as slackly disposed around the pipe P, which slack condition facilitates manipulation of the chain end in attaching the same to the coupler arms. The attachment of the chain end to the coupler arms is accomplished by passing the same upwardly 50 between the coupler arms 23 and then selectively engaging oppositely projecting coupler studs 20 of the chain with either of the hooks 24 of said coupler arms.

The wrench or tongs having been operatively applied to pipe P in the manner above described, 55 the operator thereupon swings the lever member 14, by means of its handle extension 17, downwardly or in clockwise direction. The initial downward movement of the lever member 14 overcomes the holding resistance of the 60 detent balls 31-35 and permits lever member to turn relative to the head 10, whereby the upward swing of the lever extension 16, transmitted through the link 26, turns the coupler members 22 in anti-clockwise direction about their 65 pivotal connection with the head 10, thus swinging outward the coupler arms 23 away from the pipe P. This movement of the coupler arms 23 draws upon the attached chain end so that the 70 chain 19 is constricted about the pipe P in grip-

ping relation thereto (see Fig. 4). Once the pipe P is thus gripped continued clockwise movement of the lever member 14 is transmitted to the head 10 and chain 19, whereby the pipe P is turned.

Upon completing an operative stroke of the wrench or tongs in the manner explained, it then being desired to retract the wrench or tongs to recover initial position for a fresh bite upon the pipe and repetition of an operative pipe turning stroke of the wrench or tongs, the operator swings the lever member 14, by means of its handle extension 17, in a retractive upward or anti-clockwise direction. The initial phase of such movement turns the lever member 14 relative to the head 10 until the detent balls 31-35 again 15 interlock these parts in normal initial relation. This initial movement swings downward the lever extension 16 to turn the coupler members 22 in clockwise direction, thus swinging the coupler arms 23 inwardly toward the pipe P. Such movement of the coupler arms slackens the chain 19 and relaxes its grip upon the pipe, whereupon 20 continued upswing of the lever member 14 is transmitted to the head and chain, causing the latter to slip around the pipe until the initial 25 position of the wrench or tongs is regained, whereupon an operative stroke of the wrench effective to rebind the chain in gripping relation to the pipe and then to turn the latter is repeated.

It will be obvious from the above description, 30 that a very simple and yet highly efficient wrench or tongs is provided by the instant invention, the same being automatic in its action, as controlled by its hand lever, to operatively grip or 35 release the pipe, as the case may be, and consequently permitting repeated operative strokes calculated to turn the pipe step by step, or with a ratchet-like mode of operation.

I am aware that some changes may be made 40 and apparently more or less widely different embodiments of this invention could be made without departing from the scope thereof as defined in the following claims. It is therefore intended 45 that all matter contained in the above description or shown in the accompanying drawing shall be interpreted as illustrative and not in a limiting sense.

I claim:

1. In a wrench tool, a head having divergent 50 work engaging jaw portions at its forward end, a rearwardly extending hand lever member pivotally connected with the rearward end of said head, said lever member having an extension projecting forwardly from its pivot point, a work gripping chain anchored by one end to one jaw portion of said head, a chain coupler bell-crank pivotally connected with the other jaw portion of said head, the outer arm of said coupler bell-crank having chain engaging hook means, and 55 link means interconnecting the inner arm of said coupler bell-crank to the forward extension of said lever member, whereby initial movement of said lever member in work turning direction swings said coupler bell-crank about its fulcrum in a direction to constrict the chain to work gripping tension, while movement of said lever member in the opposite direction swings said coupler bell-crank in a direction to relax said chain for slip relative to the work.

2. In a wrench tool, a head comprising laterally spaced head plates each having divergent work engaging jaw portions at its forward end, a rearwardly extending hand lever member pivotally connected to and between the rearward 60

end portions of said head plates, said lever member having an extension projecting forwardly between said head plates from its pivot point, a work gripping chain anchored by one end to and between the head plate jaw portions at one side of the head, a chain coupler means comprising a bell-crank structure pivotally mounted between the head plate jaw portions at the other side of said head, the outwardly extending branch of said bell-crank structure having chain engaging hook means, and link means interconnecting the inwardly extending branch of said bell-crank structure to the forward extension of said hand lever member.

3. A wrench tool as defined in claim 2, having detent means for yieldably interlocking said head and hand lever member in normal initial positions against relative movement, said means comprising the provision in said lever member of a transverse bore therethrough offset relative to the fulcrum point thereof and extending between the head plates, check balls respectively mounted in the respective ends of said bore, spring means intermediate said check balls, and the inner faces of said head plates having check ball engageable seats.
